Primary Examiner — Jack Reickel*Assistant Examiner* — Sydney M Evans(74) *Attorney, Agent, or Firm* — Stevens Patent Law LLC; James Stevens(57) **CLAIM**

The ornamental design for a trimmer line spool, as shown and described.

DESCRIPTION

FIG. 1 is a front, right and top perspective view of a trimmer line spool showing my new design;

FIG. 2 is a back, left and bottom perspective view thereof;

FIG. 3 is a bottom perspective view thereof;

FIG. 4 is a front elevation view thereof;

FIG. 5 is a back elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines depict portions of the trimmer line spool that form no part of the claimed design.

1 Claim, 9 Drawing Sheets(56)
